MOUTHPIECE ADJUSTER

Filed May 12, 1924

FIG. 1.

FIG. 2.

FIG. 4.

FIG. 3.

INVENTOR

Earl L. Simpson

BY

William W. Varney
ATTORNEY

UNITED STATES PATENT OFFICE.

EARL L. SIMPSON, OF BALTIMORE, MARYLAND.

MOUTHPIECE ADJUSTER.

Application filed May 12, 1924. Serial No. 712,595.

The object of my invention is the providing a securing and adjusting means to attach a mouthpiece to a mouthpipe of a wind instrument, especially the saxophone.

5 A further object of my invention is an improved adjusting bit or sleeve in the adjustment of the relative positions of the mouthpipe and mouthpiece of wind instruments.

10 A further object of my invention is an improved securing means of attaching and securing a mouthpiece to a musical instrument.

15 A further object of my invention is an improved means of making tight, both air and mechanically, a mouthpiece on a musical instrument.

With the foregoing and other objects in view, my invention consists of the novel construction, combination and arrangement of parts as hereinafter specifically described and illustrated in the accompanying drawing, wherein is shown the preferred embodiment of my invention, but it is understood 25 that changes, variations and modifications can be resorted to which come within the scope of the claims hereunto appended.

In the drawing of the herein-described embodiment of my invention, Fig. 1 is a view 30 in elevation of a saxophone mouthpipe, adjusting bit, securing means, washer and mouthpiece. Fig. 2 is a view of the same parts as shown in Fig. 1 assembled in operative position, shown partly in section. Fig. 35 3 is a sectional view taken through 3—3 of Fig. 2; and Fig. 4 shows a modified form of attaching the mouthpiece.

Similar numerals refer to similar parts throughout the several views.

40 1 is the mouthpiece of a musical instrument provided, as is usual, with a tapered end, omitting, however, the resilient or cork sleeve. 2 is the adjusting sleeve or covering preferably tapered on the inside to fit the mouthpipe 1 and cylindrical on the outside to permit securing means or mouthpiece sleeve 3 of the mouthpiece attachment to be slid upon the same and adjusted in any position thereof and secured. 4 is the mouthpiece which is secured in this case by attaching means 5. 6 is a washer to make the joint tight between attaching means 5 and mouthpiece 4. Attaching means 3 and 5 are provided with pairs of lugs 7 and 8

for pinching the adjusting means by means 55 of thumb screws 9 and 10; between said adjusting lugs the adjusting means is slit to permit of this pinching or adjustment.

Adjusting means 3 and 5 may be made integral with mouthpiece 4, in which event 60 attaching means 5 is substantially omitted, attaching means 3 being the only one necessary to secure the mouthpiece in adjustment on bit 2.

I do not wish to limit myself to any particular type of musical instrument or mouthpiece or means of making the same wind-tight in its attaching.

Having thus described my invention, what I claim and desire to secure by Letters Patent is:

1. In combination, a musical instrument mouth-pipe, a mouth-piece and means of securing said mouth-piece to said mouth-pipe consisting of, a sleeve cylindrical externally 75 and provided internally to fit said mouth-pipe, and means provided on said mouth-piece to permit the adjustment of the same over said sleeve, the said means being provided with an external clamping means 80 operating on the exterior of said mouth-piece, and means of making the joint between the said means and said mouth-piece air-tight by said external clamping means.

2. In combination, a musical instrument 85 mouth-pipe, a mouth-piece, means of securing said mouth-piece to said mouth-pipe consisting of a sleeve cylindrical externally and provided with means internally to fit said mouth-pipe, means provided on said mouth-piece the said means being provided with a clamping means operating on the exterior of said sleeve to permit the adjustment of the same over said sleeve, and means of securing the same when so adjusted.

3. In combination, a musical instrument mouth-pipe a mouth-piece, means of securing said mouth-piece to said mouth-pipe consisting of, a mouth-piece sleeve provided on the exterior thereof with an off-set 100 flanged portion to fit over said mouth-piece and means of making said sleeve air-tight with reference to said mouth-piece and a covering for said mouth-pipe cylindrical externally and over which said sleeve operates, and means of relatively securing said mouth-piece sleeve on said cover.

EARL L. SIMPSON.
